TOBACCO CONTAINER

Lucien D. Sparks and Matthew J. Levitt,
Minneapolis, Minn.

Application June 5, 1933, Serial No. 674,408

6 Claims. (Cl. 206—41)

Our invention relates to containers or packages and particularly to tobacco containers.

Tins in which tobacco is ordinarily sold are bulky and inconvenient to carry in the pocket of an article of clothing and occupy the same amount of space irrespective of the portion of the original contents remaining therewithin. In filling a pipe from such a tin it is not possible to dip a pipe in the contained tobacco but instead the tobacco must be poured or otherwise conveyed from the tin to the pipe with resultant inconvenience and spillage. Also, a prospective purchaser of such a tin of tobacco cannot see the color and texture of the tobacco contained therein while the tin is closed.

An object of our invention is to provide a tobacco container of compact, envelope-like form capable of efficiently protecting its contents against dust and loss of moisture content and affording a view of a portion of its contents.

Another object is to provide such a container having an inner envelope or pouch for containing tobacco and an outer envelope or protective covering wherein opening or closing of the outer envelope acts to simultaneously open or close the inner envelope.

Still another object is to provide such a container which, when closed, maintains the inner envelope thereof substantially sealed against entrance or exit of air and wherein such sealing is effective after repeated opening and closing.

A still further object is to provide such a container which may be easily and cheaply constructed, which is of convenient shape to be carried in the pocket of an article of clothing, and which is so arranged that access to its contents may be readily had, as for filling a pipe, with relatively little danger of damaging the container.

These and other objects and advantages of the present invention will more fully appear from the following description, made in connection with the accompanying drawing, wherein like reference characters refer to the same or similar parts throughout the various views, and in which:

Fig. 1 is a front view of our container;

Fig. 2 is a rear view;

Fig. 3 is an end view of our container when the same is opened;

Fig. 4 is an enlarged vertical cross-sectional view taken along the line 4—4 of Fig. 1 as indicated by the arrows;

Fig. 5 is a horizontal sectional view taken along the line 5—5 of Fig. 2 as indicated by the arrows, 55 and

Fig. 6 is a view of the blank from which the outer portion of the container is formed.

Referring to the drawing, the outer envelope or protective covering of our tobacco container is constructed from a blank, such as shown in Fig. 6, formed of non-transparent, comparatively flexible material such as cardboard, heavy cloth or the like. The blank includes a back 10, a front 11 and a flap 12. A narrow strip 13 extends outwardly from the free edge of the back 10. A tongue 12a extends outwardly from the medial portion of the free edge of the flap 12. End flaps 14, shaped as shown in Fig. 6, extend outwardly from the ends of the front 11.

In assembling the outer envelope the blank is 15 folded along the line b to bring the back 10 and the front 11 adjacent each other in parallel relation. The blank is reversely folded along the line c to bring the protective strip 13 into parallel relation with the upper portion of the exterior 20 side of the back 10 and thus form a rounded sealing edge at the line c. The blank is reversely folded on the line d to bring the flap 12 into parallel relation to the back 10. A slit 15 is formed in the back 10 in proper location to receive the 25 tongue 12a of the flap 12 as shown in Figs. 2 and 4. It will of course be understood that other securing means such as a snap button or other means may be employed in place of the combination comprising the tongue 12a and the slit 15. 30

Each end flap 14 is folded on the lines e, f, g and h, as best shown in Fig. 5, to adapt the same for bellows-like action. The outer end section 14a of the end flap 14 is then attached to the inner side of the back 10 by means of an adhesive or 35 other suitable means.

The connections between the corresponding ends of the front 11 and the back 10 by means of the end flaps 14 obviously permit changing the distance between the front and back in accordance with the quantity of material contained in the container.

The front 11 is provided with a viewing aperture 16 as shown in Figs. 1 and 6.

The inner envelope 17 is a rectangular envelope 45 of any desired form constructed of relatively thin flexible preferably transparent sheet material. The inner envelope 17 is of such dimensions and is so inserted in the interior of the outer envelope that its open edged portion will extend 50 adjacent to the flap 12 a substantial distance above or outwardly of the sealing edge on the line c at the open upper end of the outer envelope. The medial portion of the front side of the open edged portion of the inner envelope 17 is 55

secured to the flap 12 by adhesive means or other suitable means. It is to be noted that only the medial portion of the upper edge of the inner envelope 17 is secured to the flap 12 so as to permit opening the upper end of the inner envelope to a substantially oval shape for providing convenient access to the contents without danger of tearing the inner envelope.

The side edge portions of the inner envelope 10 17 are disposed between the two centermost sections of the bellows-like end flaps 14 as shown in Fig. 5.

When the container is filled for use, tobacco, indicated at T, or other material, is placed within 15 in the inner envelope 17 and the flap 12 is bent or folded downwardly over the back 10 of the outer envelope to the position shown in Figs. 2 and 4. As the flap is folded downwardly the outwardly protruding open edged portion of the inner envelope 17 is of course carried therewith. The inner envelope is thus folded on a line adjacent the folded sealing edge at the upper end of the back portion 10 to effect a substantially 20 air tight closure of the inner envelope. The fold in the outer envelope at the line c (where the strip 13 joins the back 10) provides a sufficiently rounded sealing edge to protect the inner envelope 17 from being cut along the line on which it is folded over the sealing edge. When the 25 container is closed the tongue 12a on the flap 12 is inserted through the slit 15 in the back 10 of the outer envelope as shown in Figs. 2 and 4, to retain the flap 12 in closed position.

It is apparent that the color and texture of a 30 portion of the contents of the container will be visible through the viewing aperture 16 in the outer envelope and the transparent material of the inner envelope 17.

When the container is opened for removal of 35 a portion of its contents the tongue 12a is withdrawn from the slit 15 and the flap 12 is swung upwardly to the position shown in Fig. 3 or therebeyond. The folded portion is obviously swung upwardly with the flap 12 and the open edge of the inner envelope 17 is hence made available for access to the interior of the inner envelope.

If desired the container may be repeatedly closed and opened and each time it is closed the folding of the inner envelope 17 at the sealing 40 edge along the line c will be effective to produce a substantially air tight seal to protect the contents against dirt or dust and against gain or loss in moisture content.

It is obvious that the folded arrangement of 45 the end flaps 14 will permit the distance between the front 11 and the back 10 to vary in accordance with the amount of tobacco contained in our container and thus at all times permit our container to occupy a minimum amount of space. Also, since the upper edge portion of the inner envelope 17 is secured to the flap 12, only at the 50 medial portion of one side thereof so as to permit the upper end of the inner envelope to be opened to a substantially oval shape, a pipe may be conveniently dipped into the contained tobacco for filling without danger of tearing or otherwise damaging the container.

While our container is particularly adapted for 55 use as a container in which tobacco may be sold and in which tobacco may be carried by the user thereof, it is apparent that it is also well adapted for use as a container for many other kinds of materials.

Obviously the inner envelope may be formed 60 of non-transparent material which is so treated

as to become transparent in the portion thereof registering with the viewing aperture in the outer envelope. Also, the viewing portion of the outer envelope may be formed by treating that portion to make the same transparent instead of forming 5 an aperture in that portion.

It is apparent that we have invented a novel, compact, simple and inexpensive form of container for tobacco and the like from which a pipe may be conveniently filled and which includes 10 means for displaying the color and texture of the contents thereof without opening the same, means for repeatedly opening and closing the same with great convenience, and means for effectively sealing the same when closed. 15

It will, of course, be understood that various changes may be made in the form, details, proportions and arrangement of the parts without departing from the scope of our invention, which, generally stated, consists in a device capable of 20 carrying out the objects above set forth and in the novel parts and combinations of parts disclosed and defined in the appended claims.

What is claimed is:—

1. A container of the class described comprising 25 an envelope having an extended open ended portion and constructed of thin flexible material, a member having a portion folded upon itself to form a thicker sealing edge disposed below the upper end of said envelope about the folded edge 30 of which said extended portion may be folded to effect sealing of said envelope and means for retaining the folded portion of said envelope in closed position.

2. A container of the class described comprising 35 an inner envelope constructed of thin flexible material disposed within an outer envelope, said outer envelope including a front and a back joined along their lower edges, a swingable closure flap extending outwardly from the free edge of 40 one of said members, the other of said members having a straight sealing edge opposite said closure flap, and said inner envelope extending outwardly beyond said sealing edge and having an open outer end whereby swinging of said closure flap to its closed position will result in the outer portion of said inner envelope being folded over 45 said sealing edge to effect the sealing of said inner envelope.

3. A tobacco container comprising an inner 50 envelope disposed within an outer envelope, said outer envelope including a front member and a back member, a swingable closure flap extending outwardly from the free edge of one of said members and a narrow flap extending from the 55 free edge of the other of said members, said narrow flap being reversely folded to form a sealing edge at the fold therein, said inner envelope extending outwardly beyond said sealing edge and having an open outer end, the medial portion of 60 the upper edge of the side of said inner envelope adjacent said closure flap being secured to said closure flap whereby swinging of said closure flap to its closing position will cause the outer portion of said inner envelope to be folded over said sealing edge and swinging of said closure flap to its open position will swing the outer portion of said inner envelope to its unfolded position.

4. A tobacco container comprising an inner envelope disposed within an outer envelope, said 70 outer envelope including a front member and a back member joined along their lower edges, a swingable closure flap extending outwardly from the free edge of one of said members and a narrow flap extending from the free edge of the other 75

of said members, said narrow flap being reversely folded to form at the fold therein a continuous sealing edge along the free edge of said other member, and said inner envelope extending outwardly beyond said sealing edge and having an open outer end whereby swinging of said closure flap to its closing position will result in the outer portion of said inner envelope being folded over said folding edge to effect sealing of said inner envelope.

5. A tobacco container comprising an inner envelope disposed within an outer envelope, said outer envelope including a front member and a back member integrally connected along their lower edges and connected at corresponding side edges by means of multiply folded elements whereby the distance between the respective medial and upper portions of said outer envelope may be varied, a swingable closure flap extending outwardly from the free edge of one of said members and a narrow flap extending from the free edge of the other of said members, said narrow flap being reversely folded to form a sealing edge at the fold therein, and said inner envelope extending outwardly beyond said sealing edge and having an open outer end whereby swinging of

said closure flap to its closing position will result in the outer portion of said inner envelope being folded over said folding edge to effect closure of said inner envelope.

6. A tobacco container comprising an inner envelope disposed within an outer envelope, said outer envelope including a front member and a back member integrally connected along their lower edges and connected at corresponding side edges by means of multiply folded elements 10 whereby the distance between the respective medial and upper portions of said outer envelope may be varied, means for securing said inner envelope to the inner side of one of said members, a swingable closure flap extending outwardly 15 from the free edge of one of said members, the other of said members having a straight sealing edge opposite said closure flap and said inner envelope extending outwardly beyond said sealing edge and having an open outer end whereby 20 swinging of said closure flap to its closing position will result in the outer portion of said inner envelope being folded over said folding edge to effect closure of said inner envelope.
